Des. 196,017

PAGE 4

Fig. 4.

Fig. 5.

FIGURE 1 is a front perspective view of an internal combustion engine embodying my new design;

FIGURE 2 is a rear perspective view thereof;

FIGURE 3 is a plan view thereof;

FIGURE 4 is a front elevational view thereof; and

FIGURE 5 is a rear elevational view thereof.

The dominant features of my design reside in those portions thereof shown in solid lines.

I claim:

The ornamental design for an internal combustion engine, as shown and described.
